BOX OR CARTON

Clifford J. Munce, London, Ontario, Canada

Application June 9, 1934, Serial No. 729,761

7 Claims. (Cl. 229—34)

My present invention relates to boxes or cartons made of fibrous material, such as double faced kraft board, and more particularly to an improved box or carton made from a single blank 5 of material.

In fabricating boxes or cartons from sheet material, such as paper, kraft board, or the like, it is desirable that the blank from which the box or carton be made, should be as nearly rectangular as possible, in order that the waste of material be kept to a minimum. With the present day necessity for hand holds in boxes and cartons of any considerable size, the waste of material has increased despite the fact that a rectangular 15 blank may be used. Also, as the cutting and scoring of the blank is done by a die structure, the necessary cutting and stripping devices for blanking out openings for hand holds has materially increased the cost of the boxes or cartons, besides 20 materially slowing down the production thereof.

In my present invention, I have obviated the objections to prior methods of manufacturing boxes or cartons, and have succeeded in making a box or carton of pliable fibrous material, such 25 as double-faced kraft board, from a rectangular blank, and cut and score the blank by a simple die, and avoid entirely the necessity of any cut-out portion that would require blanking out and stripping devices as a part of or accessory to, the 30 die structure.

In carrying out my invention, I utilize a rectangular blank, cut and scored to define the various elements of a box or carton, and by folding the various elements into proper position and 35 relation to each other, produce a box or carton in which the sides and ends thereof are double reinforced, and in which hand holds are automatically formed by folding reinforce elements into engagement with the ends of the box, and which 40 elements interengage with themselves and with the reinforce for the sides of the box or carton, to thereby prevent displacement regardless of the load within the box or carton.

An object of my invention therefore, is an improved 45 box or carton made from a blank of fibrous material.

Another object of my invention is an improved box or carton made from a blank of sheet material and having a hand hold formed therein during 50 the assembling thereof.

Still another object is an improved box or carton made from a blank of sheet material and being reinforced about its sides and ends, and in which the reinforcing elements are mutually 55 interlocked.

Other objects and novel features of the construction and arrangement of parts comprising my improved structure will appear as the description of the invention progresses.

In the accompanying drawings,

Fig. 1 is a plan view of a blank from which a box or carton is constructed;

Fig. 2 is a perspective view of the blank, showing one side and end in partially assembled position and partly broken away;

Fig. 3 is a perspective view of the blank, showing a practically completed box or carton;

Fig. 4 is a plan view of a blank from which the cover for the box or carton, illustrated in Fig. 3, is made, and

Fig. 5 is a perspective view of a cover in process of construction.

Referring to the drawings, 10 designates a blank, made from any suitable flexible sheet material, such as cardboard, double faced kraft 20 board, and the like. Centrally located in the blank 10, which is rectangular in form, is a box or carton bottom 11, defined by the scored lines 12, 13, 14 and 15. The bottom 11 may be of any desired shape, but preferably rectangular. 25 Formed of the blank 10, and at the opposite ends of the bottom 11, are the box or carton ends 16 and 17, the end 16 being separated from the bottom 11 by the scoring 12, and the end 17 being likewise separated by the scoring 14. Formed at 30 the ends of the box or carton end 16 are wings 18 and 19, such wings being triangular in shape and divided from the end 16 by a scored line 20, in alignment with the scored line 13, and a scored line 21, in alignment with the scored line 15, 35 respectively. Formed at the ends of the box or carton end 17 are wings 22 and 23, similar to the wings 18 and 19, these wings 22 and 23 being divided from the end 17 by the scored lines 24 and 25 respectively, the scored line 24 being in 40 alignment with the scored line 13 and the scored line 25 being in alignment with the scored line 15.

Formed of the blank 10 and divided from the bottom 11 by the scored line 13, is a box or carton 45 side 26, of a length equal to the length of the bottom 11, and of a width equal to the width of the box or carton ends 16 and 17. Formed of the blank 10 is a box or carton side reinforce 27, divided from the box or carton side 26 by the 50 scored line 28 which is parallel to the scored line 13. The width of the reinforce 27 is substantially equal to that of the side 26 and the length is slightly less than the length of the side 26. At one end of the side 26 and divided therefrom by 55

the scored line 29 is a hand hold member 30, this member being separated from the wing 18, during the dieing operation of forming the blank 10, by a line of cut 31. Formed integral with the hand hold member 30 and separated therefrom by the scored line 32, is a locking member 33, this locking member being spaced apart from the end of the reinforce 27 by the cut-out 34.

At the opposite end of the side 26 is arranged 10 the hand hold member 35, divided from the side 26 by the scored line 36, and from the wing 22 by the line of cut 37. Integral with the hand hold member 35 and divided therefrom by the scored line 38 is the combined reinforcing and locking 15 member 39 that is spaced from the reinforce 27 by the cut-out 40.

The arrangement of side, reinforce, handholds and locking members just described is duplicated on the opposite side of the bottom 11, the other 20 side being designated 41, the reinforce attached thereto 42, the scored line between the side and reinforce being 43, the handhold members being designated 44 and 45 respectively, divided from the side 41 by the scored lines 46 and 47 respectively. The hand holds 44 and 45 are separated 25 from the wings 19 and 23 by the lines of cut 48 and 49 respectively. Attached to the hand hold member 44 and divided therefrom by the scored line 50 is the locking member 51, this member 30 being spaced from the end of the reinforce 42 by the cut-out 52. Attached to the hand hold member 45 and divided therefrom by the scored line 53 is the locking member 54, this member 35 being spaced from the end of the reinforce 42 by the cut-out 55.

In the side member 26, centrally thereof and adjacent to the scored line 28, is a slot 56 through which may be passed a strap forming a handle for the box or carton to be constructed from the 40 blank 10. A similarly situated like slot 57 is formed in the side member 41.

58 designates a strap or handle, preferably made from a folded strip of fibrous material, the ends of which pass through the slots 56 and 57 45 and may be fastened to the sides 26 and 41 by staples 59, or in any other convenient manner. An alternative type of fastener is shown in Fig. 3, where a metal clip or hook 60 is shown attached to one end of the strap 58, the hook being adapted 50 to engage with the lower edge of the reinforce members 27 and 42.

By reference to Fig. 1 it will be noted that the blank 10 is rectangular and the only material wasted from the sheet of material from which the 55 blank is formed is the space adjacent to the hand hold members 30, 35, 44 and 45, the locking members 33, 39, 51 and 54, and the cut-outs 34, 40, 52 and 55. Also, it will be noted that no portion of the blank 10 necessitates the cutting out of material by a complicated die structure. The blank 10 therefore, may be produced by a simple die, without appreciable waste and at a minimum cost.

Assuming the blank 10 to have been formed as 60 above described, and that it is desired to assemble the same into box or carton form, one of the ends, as the end 17, is folded about the scored line 14 into a position perpendicular to the bottom 11, and the wing 23 is folded about the scored line 25 into a position perpendicular to the end 17, 65 and the bottom 11, as shown in Fig. 2. A similar 70 operation is then performed with respect to the end 16, and wing 19. The side member 41 is then folded about the scored line 15 into a position perpendicular to the bottom 11 and into engagement 75 with the now outer faces of the wings 23 and 19.

The reinforce 42 is now folded about the scored line 43 into a position within the box or carton and into parallelism with the side 41, this operation resulting in enclosing the wings 23 and 19 within the side 41 and reinforce 42.

Similar operations are then performed on the wings 22 and 18, the side 26 and reinforce 27.

To complete the box or carton structure the hand hold members are folded about their respective score lines 20, 21, 24 and 25 to bring such 10 members into position against the outer face of the ends 16 and 17, after which the locking members 33, 39, 51 and 54 are folded into position against the inner face of the ends 16 and 17. This latter operation is clearly shown in Fig. 3, where 15 the locking member 54 is shown in its final position against the inner face of the end 17, and with its outer edge locking the reinforce 42 in position. Also, the locking member 39 is shown in Fig. 3, in position preparatory to folding into 20 final position, and it will be apparent that when it is in final position, it will lock the reinforce 27 in its final position, and the locking members 54 and 39 will engage with each other so as to prevent 25 accidental displacement of the parts.

Referring again to Fig. 3, it will be noted that the hand hold members 44 and 30 engage with each other to assist in holding the parts in proper position and these members cooperate to produce an efficient hand hold, the resiliency of the material, such as double-faced kraft board, readily permitting the insertion of the fingers of the hand 30 of the operator between the hand hold members and the outer face of the end.

There is thus produced from a rectangular 35 blank, a box or carton in which the sides and ends are reinforced, and in which hand holds, formed integrally with the material of the box or carton, are arranged at opposite ends of the box or 40 carton.

Referring now to Fig. 4, there is shown in plan 45 view a top blank, made from a sheet of fibrous material, preferably double-faced kraft board, and comprising a top 62, rectangular in form and of a size to make a suitable cover for the box or 50 carton illustrated in Fig. 3. This top 62 is provided at its ends with end members 63 and 64, divided from the top 62 by scored lines 65 and 66 respectively. Formed integral with the material of the ends 63 and 64 and divided therefrom by scored lines 67 and 68 respectively, are locking 55 and reinforce members 69 and 70 respectively.

On the sides of the top 62 are arranged sides 71 and 72 divided from the top by scored lines 73 and 74 respectively. These sides 71 and 72 have attached at their ends extensions 75 and 76 divided from the sides by scored lines 77. Centrally arranged in the top 62 and extending transversely thereof is a slot 78 and through which may extend the strap or handle 58. The blank from 60 which the top is cut is rectangular in shape and no cut-outs, other than the slot 78 and the space between the sides of the extensions 75 and 76 and the ends of the sides and reinforces 63, 64 and 69 and 70 are necessary. None of such cut-outs 65 necessitate the use of a stripping device on the die, and therefore, the die is of simple character and the blank is produced rapidly and without 70 waste of material.

In forming the blank shown in Fig. 4 into the 75 box or carton top shown in Fig. 5, the sides 71 and 72 are folded on the scored lines 73 and 74 respectively, into a position perpendicular to the top 62, the extensions 75 and 76 are folded on the scored line 77 perpendicular to the sides, after 75

which the ends 63 and 64 are folded on the scored lines 65 and 66 into engagement with the extensions 75 and 76. The reinforce members 69 and 70 are then folded on the scored lines 67 and 68, thus clasping the extensions 75 and 76 against the inner face of the ends 63 and 64 respectively.

The resulting cover, when put on the box or carton shown in Fig. 3, has the slot 78 positioned over the strap or handle 58 and such handle, projecting through the slot 78 may be used as a means for carrying the box or carton.

The blanks from which the box or carton and cover are made, may be assembled at the factory and shipped to the customer ready for use, or 10 may be shipped flat to the customer, who may assemble them as needed.

I claim.

1. A box of pliable sheet material formed from a single blank and having a rectangular bottom 20 fold and flaps extending respectively from the several edges of said fold and constituting the sides and ends of the box, side reinforce members arranged at the upper ends of the sides and foldable within the box, wings at either end of the 25 ends of the box and foldable into the space between the sides and reinforce members, a hand hold member and a combined end reinforce and locking member at each end of the side members, said hand hold members folding on the outer 30 face of the box end, and the locking members folding within the box and occupying the entire space between the sides of the box adjacent the ends, whereby the side reinforce members and combined end reinforce and locking members are 35 locked in operative position.

2. A box of pliable material formed from a single blank and having sides and ends, a reinforce member for each of the sides, and a hand hold member and a combined locking member and end 40 reinforce formed integral with each side.

3. A box of pliable material formed from a single blank and having sides and ends, a reinforce member for each of the sides, and a combined end reinforce and locking member formed integral 45 with each of the sides at each end thereof, the combined end reinforce and locking members at each end of the box folding into a position on the inside of the box and filling the space between the side reinforce members, with their adjacent edges engaging each other and with their opposite edges engaging the side reinforce members respectively, whereby to lock the side reinforce members in position and themselves against accidental displacement.

55 4. A box of pliable material formed from a single blank and having sides and ends, a reinforce member for each of the sides, and a hand hold member and a combined end reinforce and locking member formed integral with the sides at each 50 end thereof, and the combined end reinforce and

locking members at each end of the box folding into a position adjacent to each other against the inner face of the box ends and occupying the entire space between the side reinforce members and having adjacent edges engaging each other 5 and opposite edges engaging the side reinforce members, whereby to lock the side reinforce members in position and themselves against displacement, the hand hold members at each end of the box folding into a position against the outside 10 of the box, to form a hand hold, the hand hold members being locked in position by the end reinforce members.

5. A box or carton made from a single blank of pliable sheet material and having sides and 15 ends, reinforce members for the sides formed integral therewith and adapted to fold about the upper edge of the sides to a position within the box and against the inner face of the sides, and members formed integral with and at each end of 20 each of the sides, such members comprising a hand hold member and a combined reinforcing and locking member, the hand hold members at each end of the box folding against the outer 25 face of the box end and constituting a hand hold, and the reinforcing and locking member folding into position against the inner face of the box end, such locking members abutting against each other and against the reinforce members for the 30 sides to thereby hold the reinforce members in position and the locking members against displacement.

6. A box or carton made from a single blank of pliable sheet material and having sides and 35 ends, hand hold members for the ends of the box formed integral with and at each end of the sides, the hand hold members at each end of the box being folded into position adjacent and parallel to the outer face of the box end, and the lower edge of each hand hold member being cut away 40 on a line extending from the lower corners of the box end to a point slightly below the middle of the upper edge of the box end, and a locking means for said hand hold members formed integral therewith and arranged against the inner 45 face of the box ends, with their adjacent edges in engagement with each other, and their opposite edges in engagement with the sides of the box.

7. A box of pliable sheet material formed from 50 a single blank and having sides and ends, and reinforce members formed integral with the sides, said reinforce members, when in operative position, filling the space between the sides of the box, with their adjacent edges abutting each 55 other, and with their opposite edges engaging with the sides of the box, whereby accidental displacement of the reinforce members is prevented.
